(57) **CLAIM**

The ornamental design for a light module for firearm, as shown and described.

DESCRIPTION

FIG. 1 is a rear perspective view of a light module for firearm in a use configuration showing our new design, illustrating the light module as a flashlight module.

FIG. 2 is a front view of the light module in a use configuration as the flashlight module.

FIG. 3 is a rear view of the light module in a use configuration as the flashlight module.

FIG. 4 is a right view of the light module in a use configuration as the flashlight module.

FIG. 5 is a left view of the light module in a use configuration as the flashlight module.

FIG. 6 is a top view of the light module in a use configuration as the flashlight module.

FIG. 7 is a bottom view of the light module in a use configuration as the flashlight module.

FIG. 8 is a rear perspective view of the light module in a use configuration showing our new design, illustrating the light module as a laser light module.

FIG. 9 is a front view of the light module in a use configuration as the laser light module.

FIG. 10 is a right view of the light module in a use configuration as the laser light module.

FIG. 11 is a left view of the light module in a use configuration as the laser light module.

FIG. 12 is a top view of the light module in a use configuration as the laser light module; and,

FIG. 13 is a bottom view of the light module in a use configuration as the laser light module.

The broken line portion of the figure drawings is included to show unclaimed subject matter only and forms no part of the claimed design.
